UNITED STATES PATENT OFFICE.

HOMER H. JUSTICE AND EDMUND J. O'BRIEN, OF PASADENA, CALIFORNIA.

COOLING SYSTEM FOR GAS-ENGINES.

1,347,043.

Specification of Letters Patent.

Patented July 20, 1920.

Application filed March 24, 1919. Serial No. 284,785.

To all whom it may concern:

Be it known that we, HOMER H. JUSTICE and EDMUND J. O'BRIEN, citizens of the United States, residing at Pasadena, in the county of Los Angeles and State of California, have invented new and useful Improvements in Cooling Systems for Gas-Engines, of which the following is a specification.

10 Our object is to make an air cooling system for gas engines, and our invention consists of the novel features herein shown, described and claimed.

Figure 1 is a side elevation partly in section of a gas engine provided with an air cooling system in accordance with the principles of our invention.

Fig. 2 is a fragmentary front elevation of the engine and cooling system as seen looking in the direction indicated by the arrow 2 in Fig. 1.

Fig. 3 is a fragmentary rear elevation partly in section as seen looking in the direction indicated by the arrow 3 in Fig. 1.

25 Fig. 4 is a fragmentary cross section on the line 4—4 of Fig. 1.

The water jacket 1 is constructed to make a large chamber 2 above the heads of the engine cylinders 3, and the inlet 4 from the top 30 of the radiator to the chamber 2 is vertical, there being an opening 5 through the casing leading horizontally into the chamber 2. A flange 6 fits against the casing in position to cover the opening 5 and is secured in place by bolts 7. Flue openings 8 are formed through the central portion of the flange 7 in line with the opening 5. An opening 9 is formed through the rear end of the casing in line with the opening 5, a 35 flange 10 fits against the casing to cover the opening 9 and has flue holes 11 in line with the flue holes 8, and a spout 12 extends outwardly from the flange 10 around the openings 11. Air flues 13 are screwed into the openings 11 and extend through the chamber 2 and through the openings 8, and the forward ends of the flues are expanded and tightened into the openings 8. A flexible pipe 14 connects the spout 12 to the intake

15 of the carburetor 16. A funnel 17 is secured to the flange 6 and extends forwardly in position to receive the air which passes through the radiator 18.

The suction of the engine will draw air through the pipe 14, through the flues 13, 50 and through the funnel 17, and the cold air passing through the flues 13 will cool the water in the chamber 2, and the cooling of the water will warm the air and the warm air will pass through the carburetor 16 55 thereby improving the action of the carburetor and the action of the engine, and at the same time effectually cooling the hot water at the top of the engine cylinders and avoiding the necessity of the usual fan. 60

65 Various changes may be made without departing from the spirit of our invention as claimed.

We claim:

1. A cooling system for gas engines comprising air flues mounted to extend through the water jacket, and a connection between the discharge ends of the air flues and a carburetor, so that the action of the engine will draw air through the flues to cool the water 70 and warm the air.

2. Cooling system for multiple cylinder gas engines comprising, in combination with a gas engine having a cooling water jacket common to all the cylinders, air flues 80 mounted through an upper portion of the water jacket and above the cylinder heads longitudinally of the cylinders, a funnel at the forward end of the air flue for directing air thereinto and a conduit for connecting 85 the rearward end of the air flues with a carburetor of the engine.

3. A cooling system for gas engines having a cooling water jacket, air flues mounted through the water jacket above the cylinder having a forward end open to the inflow of air and a conduit for connecting a rearward end of the air flues with a carburetor of the engine.

In testimony whereof we have signed our names to this specification.

HOMER H. JUSTICE.
EDMUND J. O'BRIEN.
